LINE CASTING AND COMPOSING MACHINE

Louis M. Potts, Evanston, Ill., assignor, by mesne assignments, to Teletypesetter Corporation, a corporation of Delaware

Original application January 2, 1932, Serial No. 584,387. Divided and this application April 21, 1934, Serial No. 721,657.

38 Claims. (Cl. 199—20)

The present invention relates to linecasting and composing machines and more particularly to the automatic operation by stored conditions of linecasting and composing machines having a plurality of matrix storage magazines. This application is a division of copending application Serial No. 584,387, filed January 2, 1932, which has matured into Patent 2,057,652 granted October 13, 1936.

10 For convenience in describing the present invention, standard structures of well known commercial linecasting and composing machines, as illustrated in the accompanying drawings, will be referred to hereinafter as the principal machines, while the mechanisms which are operative for initiating the various functions of the principal machines will be referred to herein- 15 after as the control units.

The primary object of the present invention is 20 to provide a simple reliable and efficient mechanism operative in conjunction with an automatic control unit of a linecasting and composing machine for controlling, in response to a predetermined condition, the selective release of matrices from the different matrix magazines.

Briefly, one adaptation of the present invention consists in the provision of a set of shiftable release reeds that are operatively supported in a cradle member. A lever connected to said cradle member functions to shift it and its set of reeds under the actuation of a cam carried upon a control shaft that is capable of being arrested in each of two radially opposite positions. In accordance with one of its positions 30 the operating shaft through its control cam allows the shifting lever to assume one shiftable condition, while in accordance with another of its positions it allows it to assume an opposite shiftable condition.

40 In this connection, it should be understood that still other shift positions may be obtained similarly by providing additional means for arresting the shaft in various other angular positions for thereby establishing alternative alignments of the common set of matrix release elements.

The arresting of the control shaft in various radial positions is accomplished by providing a driving clutch for operating the control shaft, the driven member of which carries a beveled lug. In the path of the lug, as it describes its cyclic revolution, are presented a plurality of disengagement levers (two in the present embodiment), each having inclined surfaces which the 50 lug is adapted to encounter for causing to be

withdrawn thereby the driven portion of the clutch from the driving portion. The clutch release levers are each controlled by one of a plurality of selectable bars which in turn are selectively conditioned by a selecting mechanism of the control unit, as described in the parent application referred to above.

For a better understanding of this invention reference will be had to the accompanying drawings and to the following detailed specification 10 wherein corresponding elements are designated by similar reference characters throughout and wherein,

Fig. 1 is a perspective view of a linecasting and composing machine having applied thereto 15 a structure embodying features of the present invention,

Fig. 2 is a transverse sectional view of the mechanism of a principal machine illustrating one form of multiple magazine apparatus and 20 illustrating a preferred embodiment of the present invention applied thereto,

Fig. 3 is a view generally similar to Fig. 2 but illustrating an alternative structure of duplex magazine apparatus and featuring an alternative 25 application of the present invention thereto,

Fig. 4 is a detail perspective view of the clutch mechanism illustrated in Figs. 2 and 3.

Fig. 5 is a schematic wiring diagram of a control circuit as applied to a control unit such as 30 the one disclosed in the parent application, and

Figs. 6 and 7 are detail sectional views of a removable keyboard.

Commercially well known types of linecasting machine structures employing multiple or duplex magazines are illustrated in Figs. 2 and 3. In a preferred embodiment of the present invention there is contemplated the provision of a structure the principles of which may be applied with equal facility to either of these commercially well known models. Fig. 1 illustrates more or less schematically the composing mechanism of a slug casting machine, reference characters 11 and 12 denoting correspondingly the top and bottom ones of a pair of multiple magazines arranged vertically in tandem. In the structure illustrated in Fig. 2 each magazine is provided with a plurality of escapement segments 13 urged by springs 14 into their foremost positions, whereat their foreportions 15 are presented so as to engage the shoulders 16 of those matrices 17 which are in their final positions in the magazines 11 and 12 from which they may be released during subsequent selective operation. The segments 13 are actuated in an os- 40 45 50 55

cillatory motion in opposition to their springs 14 by vertically disposed release reeds 18 and 19 the former of which are associated with magazine 11 and the latter with magazine 12.

5 When actuated by the release reed 18 or 19, the segments 13 are rocked about their arcuate centers causing their rearmost portions 21 to be presented within the slots 22 of the penultimate ones of the aligned rows of matrices 17. When 10 this occurs, the foreportion 15 of each segment 13 is withdrawn from the foremost matrix 17, allowing it to gravitate into its respective one of a plurality of assembling chutes 23. Following this 15 operation and upon the withdrawal of the release 20 reed 18 or 19, the segments 13 are again permitted to respond to their springs 14, and during this transition the aforementioned penultimate ones of the matrices 17, then becoming the foremost ones, are permitted to gravitate through a 25 short distance or until the foreportions 15 are presented within the slots 22, after which the matrices are allowed to move only until said portions 15 engage the shoulders 16 thereof. Meanwhile, of course, subsequently following matrices 25 are moved into the penultimate positions in accordance with the well known practice of circulating matrix storage magazines.

Each of the release reeds 18 and 19 is provided with a downwardly projecting portion 24 30 and 25 arranged in close juxtaposition with an associated projection of the alternative magazine. In other words, the projection 24 and its associated release reed 18 communicate with an escapement segment 13 which serves a class of 35 matrices bearing certain character intaglios that usually are related to those of the magazine 12 whose escapement 13 is served by a release reed 19, the downwardly extending projection 25 of which is adjacent to the said projection 24. 40 With this arrangement, a common release reed 26 is availed of to serve each pair of projections 24 and 25 alternatively in accordance with the position in which it is placed by its supporting carriage or cradle 27.

45 The alternative positions of the release reeds 26 and cradle 27 are illustrated in solid and broken lines respectively in Fig. 2. The carriage 27 is rocked about the supporting fulcrum 28 that rests upon a ledge 29 formed with the main 50 frame structure of the principal machine.

The common release reeds 26 are moved upwardly by associated ones of a plurality of weight bars 31, as described in the parent application referred to above. These weight bars are selectively conditioned by associated ones of a corresponding plurality of selectable elements, designated generally by the reference numeral 20. In accordance with the particular embodiment, two of these elements, which have no operative 55 association with any of the weight bars 31, are delegated to the function of controlling two alternative conditions of the multi-magazine shifting apparatus described above.

These selectable elements or bars are indicated 60 by the reference characters 32 and 33 and are selectively conditioned by the placement of a set of coded selecting bars 30. Each element 32 or 33 is provided with an associated pawl 34 that is normally spring-urged (not shown) into 65 the position indicated in Fig. 2 and whereat its tooth is brought into engagement with a bell crank lever 35 or 36, the former of which is shown pivoted at 37 and the latter at 38. Each 70 of the bell cranks 35 and 36 is provided with a horizontally extending portion having an open-

ing intermediate thereof, one side of which is beveled in a conventional manner and presented in alignment radially in the path of a projection 39 carried by a hub portion 41 of the driven part of a clutch 42, see Fig. 4, through which power 5 is communicated from the driving shaft 43 to a shift operating cam 44.

Through the engagement of projection 39 with each of the bell cranks 35 and 36 the driven portion 41 of clutch 42 may be disengaged from 10 its driving position causing shaft 43 to be arrested in either one of two positions, illustrated by the position of cam 44 in solid and broken lines, during which the latter is permitted to assume either of two alternative positions. 15

When in its solid line position, as illustrated in Fig. 2, the periphery of cam 44 engaging a roller 45 that is rotatably carried by the depending extremity of a lever 46, rocks the lever counterclockwise about its pivot 48, and causes 20 it through its upper extremity and link 47 to rock cradle 27 in a similar direction, aligning the set of common release reeds 26 with the projections 24 of the release reeds 18; but when cam 44 is arrested in its alternative position, as indicated 25 in broken lines, the roller 45 is permitted to recede, allowing lever 46 to be moved clockwise and causing it through link 47 to rock cradle 27 so as to align the common release reeds 26 with the projections 25 of individual release reeds 19. 30

As explained, the release of each bell crank 35 and 36 is executed by the tripping of its pawl 34 which may be accomplished manually or under the control of the signal responsive unit and which moves forward, when automatically 35 controlled, together with its selectable element 32 or 33 in response to the selective operation of a set of code bars 30, Fig. 1. The other of the bell cranks 35 and 36, not released, is normally maintained in its effective position and receives the 40 projection 39 causing to be withdrawn the driven portion 41 of clutch 42 in a position (in the present embodiment) 180° from its previously arrested 45 position.

The selectable elements 20, 32, and 33 may be 45 selected manually or automatically as fully described in the copending application hereinbefore identified. The manual selection of any of these elements is accomplished by means of a keyboard. Figs. 6 and 7 illustrate a removable keyboard 50 which may be installed for the purpose of affording a manual control without affecting the features of the automatic device. The keyboard includes a supporting frame 70 and a plurality of pivoted keylevers 91 arranged in staggered 55 relationship preferably corresponding to the standard typewriter keyboard practice. For each code bar 30 of the control mechanism there are provided two cooperative parallel bars 92 and 93 which are horizontally disposed for vertical movement parallelly above the corresponding code bar. As will be noted in Fig. 7, the keylevers 91 are horizontally and parallelly disposed at their 60 foremost portions 94 where they overlie the several parallel bars 92 and 93. Thus when any 65 keylever is depressed, it is adapted to engage all of the several sets of bars. One bar 92 of each set has cut therein notches 76 of varying lengths so as to leave projections 77, while the other bar 93 of each set is similarly cut but in opposite 70 relation to the first so that where the former is provided with a notch 76, the latter is provided with a projection 77 and vice versa. Accordingly, each keylever when depressed will impart a similar movement to one or the other lever of each 75

set. At each end and pivotally supported between each pair of bars is a lever 78, the corresponding horizontal arms 79 of which are similarly bent at right angles to the main body portions but reversely each from the other on the same lever so as to engage by means of the bent portions 79 the bar 92 or 93 adjacent thereto. In this manner the depression of an uppermost bar through the toggle arrangement causes the presentation 10 of the other bar of the set to the uppermost position. The several notches and projections of all the sets of bars 92 and 93 are so arranged that upon the depression of each keylever there is set up an individual condition of the several bars.

15 The levers 78 are provided with a third arm 81 perpendicular to the others and a connecting link 82 joins the arms 81 of each set so as to equalize the movement thereof. The links 82 are provided at one end with pins 83 adapted to engage secondary levers 84, the other ends of which are suitably articulated to the named code bars 30. In this manner the position of each of the primary levers 78 is relayed to its corresponding code bar as the same is induced by the keylevers 91, and the selection of a selectable element 20 to operate a weight bar and cause the release of a matrix, or the selection of one of the selectable elements 32 and 33 to initiate the operation of cam 44 is accomplished by the setting of code bars 30 under the control of bars 92 and 93 actuated by keylevers 91 just as if the particular selectable element had been selected in response to the setting of the code bars 30 from the record reader mechanism 61.

35 Thus the bars 32 and 33 being selected, manually or automatically, in the same manner as any of the other selectable bars as described in the copending application referred to above, cause to be associated one or the other of the magazines 11 or 12 with the common set of release reeds 26. This permits the selection of alternative magazines to be power executed under manual initiation or under the direction of an automatic control unit.

45 The shifting of operating lever 46 from one of its positions to the other having associated with it the movement of a considerable mass is preferably executed more slowly than is the performance of other functions under the supervision of the automatic control unit. For this reason, shaft 43 is preferably of somewhat reduced speed as in the case of the Bold-Roman operating shaft 268, described and disclosed in the parent application. For this reason also the record reader mechanism 61 is momentarily arrested while the magazine shift operation is being executed. This is to avoid having to insert blank signals in the tape to abide the completed shift operation. The record reader arresting system herein described serves a purpose similar to and differs structurally from, the record reader arresting system shown, described, and claimed in reissue Patent No. 20,410, granted June 15, 1937 to E. S. Larson.

55 A preferred method of controlling the performance of the record reader by the operation of the magazine shift apparatus is indicated in Fig. 5. Here the control circuit 62, as explained in the parent application, includes in series a number of circuit breakers all of which must be in closed condition to permit the energization of the record reader release magnet 63. The driven portion of clutch 42 is illustrated as carrying a double apex cam 64, the apices of which are so arranged that during either of the rest positions of cam 44 one or the other of said apices are in contact with

the spring blade of a contact pair 65. At other times, or when cam 44 is in motion, the apices are removed from the contacts 65 permitting them to come ajar and causing the circuit 62 to be broken. This deenergizes magnet 63 and causes the arrest of the record reader 61.

65 Included also in circuit 62 are contacts 216 and the contacts controlled by lever 361. The noted contacts are normally closed. As fully described in the parent application which matured into Patent No. 2,057,652, contacts 261 are under the control of the selector bar through which the elevator raising mechanism is released for operation. Consequently, during the operation of the elevator, contacts 261 are opened and electromagnet 63 is deenergized. Lever 361 is under the control of the em quad pull bar disclosed in the parent application and its maturing patent. Under certain circumstances, lever 361 is operated and the contact controlled thereby is opened for causing the deenergization of electromagnet 63. However, as far as the present invention is concerned, contacts 261 and the contacts controlled by lever 361 are not necessarily involved in the operation of the disclosed structure.

70 In accordance with the structure illustrated in Fig. 3 there is also shown a pair of matrix storage magazines alternatively selectable and arranged vertically in tandem. In this case, however, the magazines are themselves shiftable so as to have their escapement operating slides 71 brought into communication alternatively with a common set of pivoted release levers 72 which are actuated by release reeds 26 and a common set of assembling chutes 23. The shifting of the magazines 11 and 12 is executed through the instrumentality of a toggle system comprised of a pair of links 51 and 52 that are capable of being disposed in either of two positions, as illustrated in solid and broken lines in Fig. 3. The link 52 is anchored to a shaft 53 to which is also secured an arm 54 that is connected through a rod 55 to the lever 46. The shifting of the lever 46 in a manner similar to that described in connection with Fig. 2 and the structure illustrated therein, causes in this case the movement of the toggle linkage 51-52 into one or another of its alternative positions, and this assembly through its articulation at 56 with a supporting structure which is pivoted at 57 and which supports the magazines 11 and 12 causes the latter to be shifted so that one or another of them is brought into alignment with the chutes 23 and the release reeds 26. As in the case of the first described embodiment, a circuit controlling cam 64 may be provided for the purpose of arresting the record reader 61 during the shift operation. This obviates the necessity for having to insert blank or delay signals in the control tape.

75 Except for the difference in the connection between lever 46 and the toggle elements 51, 52, and 54, the remaining portions of the apparatus essentially embodying the principles of the present invention are quite similar to that illustrated in connection with the showing of Fig. 2. Thus it will be noted that an important feature of the present invention is its versatility whereby mechanisms built upon the principles of this invention may be easily and readily applied to various types of line composing mechanisms without materially changing their operative structure.

80 While the present invention has been explained and illustrated in contemplation of a specific embodiment, it should be understood that nu-

merous modifications and variations may be made without departing from the spirit or scope thereof. It is, therefore, intended not to be limited to any of the illustrative details of the 5 accompanying drawings nor to the specific language employed in the foregoing specification, but to be permitted instead a latitude of interpretation as indicated by the hereunto appended claims.

10. What is claimed is:

1. A composing machine including a plurality of magazines each having a set of matrix storage channels, a system of matrix release elements capable of association with the channels of any 15 one of said magazines, and means automatically responsive to stored signals for effecting relative movement between said magazines and said system of release elements.

2. In a composing machine, a plurality of magazines each having a set of channels, a plurality of matrices in each channel, a single matrix release mechanism common to corresponding channels in different ones of said plurality of magazines, and automatic means for effecting 25 relative movement between said magazines and said matrix release mechanism to bring a desired channel under the control of said release mechanism.

3. In a linecasting and composing machine, a 30 matrix release mechanism, a plurality of matrix storage magazines, means for effecting relative movement between said mechanism and said magazines, and an automatic control unit including apparatus responsive to stored signals 35 for operating said matrix release mechanism and said movement effecting means.

4. In a line composing machine, a plurality of matrix storage magazines each having a number of channels wherein matrices are received to 40 be selectively released, a set of matrix release mechanisms capable of association with the channels of any one of said magazines, means for associating various ones of said plurality of matrix storage magazines with said set of release mechanisms, and an automatic control device including means responsive to stored signals 45 for initiating the performance of said associating means.

5. In a line composing machine, a plurality of 50 matrix storage magazines, a set of matrix release devices associated with each of said magazines, a common set of actuators for said sets of release devices, and means under the control of stored signals for shifting said actuators to 55 associate them with said sets of matrix release devices of various ones of said magazines selectively.

6. In a line composing machine, a plurality of 60 matrix storage magazines, a set of matrix release devices associated with each of said magazines, a common set of release device actuators, and means under the control of stored signals for shifting said plurality of storage magazines 65 to associate them individually and selectively with said common set of release device actuators.

7. In an automatic control apparatus for initiating the various functions of a line composing 70 machine, the combination with a shifting lever for positioning an alternatively presentable organ, of an operating shaft, means associated with said operating shaft for imparting motion to said shifting lever in accordance with the position of 75 said shaft, and means responsive to stored sig-

nals for arresting said shaft in various radial positions.

8. In a linecasting and composing machine, a plurality of matrix storage magazines, and means for shifting said magazines including a shifting lever, an eccentric, a power driven shaft for rotating said eccentric and for thereby imparting motion to said lever, and selectively controllable means for arresting said shaft in various angular positions. 10

9. In a line composing machine, a plurality of storage magazines each containing a set of matrix supporting channels, a common set of release means including an element identified with corresponding channels of each of said magazines, means for associating said set of release means with each of said magazines individually including a shifting lever, a power driven shaft rotatable for imparting motion to said lever, and a plurality of arresting means for stopping 20 said shaft in various angular positions. 15

10. In a line composing machine, a plurality of matrix storage magazines, means for shifting said magazines to align each of them selectively for composing operation, and an automatic 25 control device including a signal responsive mechanism for selectively operating said shifting means.

11. In an automatic control unit for linecasting and composing machines, a mechanism for 30 performing shift conditioning operations comprising a power driven shaft, a shifting lever, a cam carried by said shaft for imparting motion to said shifting lever in accordance with the peripheral engagement between said cam and 35 said lever, and means for arresting said shaft in various angular positions for accordingly controlling the degree of movement imparted by said cam to said lever.

12. In a line composing machine, a plurality 40 of matrix carrying magazines, a composing apparatus including a plurality of matrix releasing mechanisms having associative capacity with each of said magazines, and means for associating each of said magazines with said plurality of 45 mechanisms including a magazine shifting linkage and an operating cam for moving said linkage in accordance with its arrested position.

13. In a linecasting and composing machine, an apparatus for shifting each of a plurality of 50 matrix storage magazines into line composing position including a carriage for holding a plurality of magazines, a linkage connected to said carriage, a power driven means for shifting said carriage through said linkage, means for initiating 55 the operation of said power driven means, and means independent of said initiating means for arresting said power driven means in predetermined angular positions.

14. In a linecasting and composing machine, a 60 composing apparatus, a plurality of matrix storage magazines, a shiftable carriage for holding said plurality of storage magazines, and power driven apparatus for shifting said carriages so as to bring various ones of said magazines into 65 operative relation with said composing apparatus including a rotatable actuator and means for selectively arresting said actuator in various angular positions.

15. In a linecasting and composing machine, a 70 housing affording a plurality of matrix storage chambers, a plurality of matrix release elements fewer in number than the number of said chambers, and means for associating various ones of said chambers with said elements including a 75

- power driving shifting device describing a successive communication between said elements and said chambers, and means for arresting said shifting device during its association with any 5 one of said chambers.
16. In a linecasting and composing machine, means for storing a plurality of classes of matrices, matrix release mechanisms capable of accommodating a limited number only of said classes, and means for shifting the association between said mechanisms and successive ones of said plurality of classes of matrices including a selectively operable actuator and means for arresting said actuator in various positions.
17. In a selector mechanism, a set of code bars, means for moving said code bars individually in response to associated signals, a selector control shaft, and a set of means for arresting said shaft in various angular positions, each of said 10 arresting means being under the control of one of said selectable elements.
18. In an automatic control mechanism, a function control shaft, frictional driving means for said shaft, a plurality of stop elements radially disposed for arresting said shaft in various angular positions, and a corresponding plurality of selectable elements each associated with one of said stop means and adapted upon its selection to release said shaft from its associated 15 angular stop position.
19. In a linecasting and composing machine, a plurality of matrix storage magazines, a keyboard mechanism including elements individually associated with corresponding channels in each of 20 said magazines, a record reader responsive to stored signals including means for selectively operating said keyboard mechanism, and means also associated with said record reader and responsive to certain signals for shifting the relationship between said elements and each of said 25 plurality of magazines.
20. In a matrix composing machine, a plurality of storage magazines presented for selective accessibility, a set of matrix release actuators to 30 be selectively associated with each of said plurality of magazines, an automatic control unit including a record reader mechanism, a set of code bars positioned by said mechanism, a pair of elements selectively actuated in accordance 35 with the arrangement of said code bars, and a mechanical linkage connecting said pair of elements and said actuators for shifting said actuators in accordance with the selective actuation of said elements.
21. In a composing machine, the combination including a plurality of matrix storage magazines each having a set of channels, a set of matrix release means including an actuator identified with each of said channels, and signal controlled apparatus responsive to the perforations in a tape for operatively associating said release means with each of said magazines selectively.
22. A composing machine including a plurality of magazines, a set of matrix release means including actuator reeds and delivery chutes, means responsive to certain stored signals for associating said matrix release means with each of said magazines, and mechanism for thereafter operating said reeds to release matrices 45 from said magazines in accordance with certain other stored signals.
23. In a composing machine, a plurality of magazines each having a set of matrix storage channels, a release mechanism having matrix release elements to accommodate each of said 50
- magazines individually, and means under the control of signal initiation and operative from a power source for changing the relative association of said release means and said magazines.
24. In a linecasting and composing machine, a plurality of matrix storage magazines, and means for shifting said magazines including a shifting lever, a rotatable member, a power driven shaft for rotating the member, and means for arresting the shaft in various angular positions.
25. In a linecasting and composing machine, an apparatus for shifting each of a plurality of matrix storage magazines into line composing position including a carriage for holding a plurality of magazines, a system of levers connected to said carriage, uni-directional power driven means for shifting said carriage through said levers, and means independent of said carriage for disabling said power driven means upon arrival of a selected magazine into line composing position.
26. In a linecasting and composing machine, a plurality of matrix storage magazines, means for releasing matrices, means for receiving and delivering said released matrices, levers for alternatively associating said magazines with said matrix releasing and receiving means, uni-directional power actuated means for operating said levers, and means for terminating the power actuation of said levers upon arrival of a selected magazine into operative position.
27. In a composing machine, a plurality of magazines each having a set of channels, a plurality of matrices in each channel, a single shiftable matrix release mechanism common to corresponding channels in different ones of said plurality of magazines, and power actuated means to shift the release mechanism into operative association with a desired set of channels.
28. In a linecasting and composing machine, a plurality of stationarily mounted matrix storage magazines, means selectively associative with either of said magazines for releasing matrices therefrom, and power actuated means for accomplishing the selective association of said matrix release means with either of said magazines.
29. In a linecasting and composing machine, a plurality of matrix storage magazines, a line composing mechanism including apparatus capable of being placed into communicable association with said magazines individually, a record reader responsive to stored signals for initiating the performance of said composing mechanism, means under the control of said record reader for shifting said apparatus into association with each of said magazines, and means effective during the operation of said shifting means for momentarily suspending the performance of said record reader.
30. In a linecasting and composing machine, a composing mechanism including a number of matrix release elements, a plurality of magazines, a supporting structure for said elements, means for moving said structure for thereby regulating the communicative relation between said elements and each of said magazines, a signal controlled apparatus for initiating the performance of said release elements and said moving means, and means for disabling the performance of said signal controlled apparatus during the interval of operation of said moving means.
31. In a line composing machine, an automatic control unit including a record reader, a shift 75

mechanism, a set of matrix release elements alternatively conditioned by said shifting mechanism, and means to arrest the performance of said record reader during the operation of said shifting mechanism.

5 32. In a line composing machine, a plurality of matrix storage magazines, means for releasing matrices from said magazines selectively, means for varying the association between said magazines and said matrix releasing means, a record reader mechanism for selectively controlling the matrix releasing means and the magazine association varying means, and means for interrupting the record reader mechanism during the operation of the magazine association varying means.

10 33. In a linecasting and composing machine, a plurality of matrix storage magazines each having a set of matrix storage channels, means for releasing matrices from said magazines selectively, signal controlled means for controlling the matrix releasing means, and means for interrupting the signal controlled means during a magazine selection operation.

15 34. In a linecasting and composing machine, a plurality of matrix storage magazines, a set of matrix release elements, means for shifting said magazines to bring any one into cooperative relation with said set of elements, means responsive to stored signals for controlling said matrix release elements and said magazine shifting means, and means for interrupting the signal responsive means during a magazine shifting operation.

20 35. In a linecasting and composing machine, a

plurality of matrix storage magazines to be shifted for individual effective placement, and means for shifting said magazines including a lever, a rotatable member engaged by said lever, means for rotating said member, and means for disabling said member in accordance with the placement of a magazine.

25 36. In a linecasting and composing machine, a plurality of matrix storage magazines, and means for shifting said magazines including a lever, a rotatable member engaged by said lever, means for rotating said member, and means effective as a result of rotation of said member for arresting it in predetermined angular positions.

30 37. In a linecasting and composing machine, a plurality of matrix storage magazines, and means for shifting said magazines including a lever, a rotatable member engaged by said lever, means for rotating said member, and means rotatable with said member for determining the positions of arrestment of the member.

35 38. In a linecasting and composing machine, a plurality of magazines to be shifted for individual effective placement, and means for shifting said magazines including a rotatable member, a lever operable by said member, a driving element, means for interconnecting said element and said member, means for establishing the interconnection, and means independent of the last mentioned means and effective as a consequence of rotation of said member for severing said interconnection.

LOUIS M. POTTS.
